UNITED STATES PATENT OFFICE.

CHARLES W. RIPSCH, OF DAYTON, OHIO.

JACK.

Application filed June 29, 1923. Serial No. 648,602.

My invention relates to jacks.

It is the object of my invention to provide a jack which may be readily elevated or depressed by the positive action of the operating handle.

It is an additional object to provide a jack which will descend when unlocked under the weight of the load which it is supporting.

10 It is a further object to provide a jack in which this descent may be controlled by a brake.

It is a further object to provide means of locking the jack at any point in its descent, and also means for unlocking it.

15 It is a further object to provide this combination of parts at the bottom of the jack in order to lower the center of gravity and make the jack more convenient for operation 20 with less interference to the operating handle of the jack when the jack is under load.

It is a further object of my invention to provide a jack in which the several parts are always in engagement with one another 25 and which eliminates any clutch or like mechanism for the engagement of the parts one with the other.

It is an additional object to provide a common casing for all of the jack parts, including the brake and the lock, so that all the 30 parts will be lubricated from the lubricant in a single casing.

It is a further object of my invention to provide a jack in which the several parts 35 may be readily reached without removing all of the parts in the jack.

It is my object to provide a jack which is simple, has the minimum of parts, and is 40 very strong, and in which the rate of descent is always within the control of the operator through a slight movement of the controlling handle.

It is my object to provide a jack which 45 may be immediately arrested in its movement, so that the finest adjustment may be made.

Referring to the drawings:

Figure 1 is an elevation of the jack with the cover plate over the brake mechanism 50 partially in section and partially removed;

Fig. 2 is an elevation of the jack with a quarter section removed on the line 2—2 of Fig. 4;

55 Fig. 3 is a section on the line 3—3 of Fig. 2;

Fig. 4 is a section on the line 4—4 of Fig. 2;

Fig. 5 is an end elevation of the brake and lock mechanism with the cover removed showing the brake ring partially in section to disclose the method of mounting helical 60 springs.

Fig. 6 is an elevation of the jack from the brake and lock side;

Referring to the drawings in detail:

1 is a base having a plurality of strengthening ribs 2. Upon this base is mounted a grooved plate 3 which constitutes the lower member of a cage for a ball bearing. This ball bearing consists of the plate 3 and the 70 upper plate 4 between which in suitable grooves in these plates, designated 5 and 6 respectively, are located the balls 7. Journaled in these plates is the base 8 of the main elevating screw. Fixed to this screw 75 in permanent engagement therewith and turning with it is the beveled gear 9 on which are formed the teeth 10. Resting on the gear and surrounding the stem of the screw is a spacing collar 11 above which is 80 the flight of the screw 12. The top 13 of the screw is located beneath a cap plate 14 upon which the load to be elevated rests. This plate is formed integral with a sleeve 15 which travels within the main tubular 85 casing 16 within the jack and is guided thereby. The sleeve 15 is provided with a shoulder or ring 17 against which abuts a nut 18 internally threaded at 19. This nut 90 engages with the screw 12.

The gear 9 has a cutaway portion on its under surface in order to receive a worm wheel 20 which is pinned thereto by the pins 21. This worm wheel meshes with a worm 22 mounted upon a shaft 23 which is journaled at either end as at 24 and 25 in the housing, inclosing the mechanism of the jack. On this shaft 23 is mounted a gear 26 meshing with a pinion 27 on a second shaft 28 journaled in the housing and parallel to 100 the first shaft 23. A cover plate 29 closes the housing and conceals the shaft and gears.

The gear 9 is driven by a beveled pinion 30 having teeth 31 engaging with the teeth 10 of the gear 9. This pinion is mounted 105 on a stub shaft 32 and is journaled in the housing in a collar 33 in which there is located a bearing 34. On this stub shaft is mounted a ratchet 35 with which engages a pawl 36 having an actuating head 37 and 110

a spring 38 which tends to maintain the pawl in engagement with the teeth of the ratchet 35. This pawl is carried in a casing 39 which is integral with the casing 40 which forms a socket for the reception of a jack handle 41.

Returning to the second shaft 28, it will be observed that this shaft is projected into a supplementary inclosed chamber 42. Within 10 this chamber mounted on the shaft is a brake drum 43. Surrounding the drum and slightly separated from it is the brake ring 44 having a plurality of cutaway cam shaped portions 45 in the periphery thereof. These 15 cam shaped portions are adapted to receive rollers 46 which are pressed in one direction by the helical springs 47 located in pockets 48 in the ring 44.

Projecting in these cam shaped cutaway 20 portions are the unlocking fingers 49, carried on the spider 50, which in turn is mounted upon the operating shaft 51 which projects through the cover plate 52 and is operated by a handle 53.

25 For the purpose of transporting the jack bodily, rollers 54 are mounted on one side of the base so that when the jack is tipped by a lever inserted in the socket 55, the jack may be wheeled to a new position.

30 *Operation.*—It will be observed that in the operation of this jack that the jack may be positively moved upwardly or downwardly by the ratchet and pawl and the jack lever. It is customary, however for 35 the jack to descend under the weight of the load. As it is always in engagement with the braking mechanism, unless restrained, the worm, wheels, gears, shafts and brake drum will turn, not only 40 when the jack goes up, but when the jack goes down. When the jack goes up there is no tendency of the rollers to lock or to brake the ascent but when the jack starts to descend the rollers will engage with the 45 brake drum and the cam surface, and thereby effect a braking and ultimately a locking of the parts to one another. The helical spring impels each roller to locking position.

50 In order to effect the unlocking of these rollers, the fingers 49 are moved by rotating the spider 50 to dislodge the rollers from their locking position. Upon the release of 55 these fingers from the rollers they are returned to the braking or locking position when the jack is descending.

The spider is impelled to its inoperative position by the spring 56.

This spider is controlled by the shaft 51 and the hand-lever 53, which is closely adjacent to the hand of the operator.

It is thus possible to effect a perfect adjustment of the descent of the jack.

This brake and lock will catch at any 65 point, will immediately take hold with the

minimum of lost motion, and the strain of stopping will be put directly on the screw. By varying the extent of the frictional engagement of the rollers and by varying the position of the fingers 49 on the spider, the 70 exact extent of the braking action may be regulated.

In this jack it is possible to handle economically the lighter tonnages in the neighborhood of fifteen tons, and also it is possible 75 to handle the heavier tonnages of seventy-five to one hundred tons.

By this arrangement the elevating is secured through the gearing which gives a 80 relatively high rate of elevation while the descent is regulated at a slower rate through the worm wheel and worm and the braking and locking mechanism.

I do not desire to confine myself to the 85 particular details as hereinbefore described, but comprehend within my invention a suitable modification thereof for its practice.

Having thus fully described my invention, what I claim as new and desire to secure by Letters Patent, is:—

1. In a jack, a vertically extending elevating member, means to operate said elevating member, a worm wheel mounted on said elevating member and turning therewith in either direction, a supplementary shaft 90 mounted in a plane adjacent the lower end of said elevating member, a worm carried by said shaft and adapted to be engaged by said worm wheel, means for braking the descent of said elevating member, and means operated by said supplementary shaft for actuating said breaking means.

2. In a jack, a vertically extending elevating member, means to operate said elevating member, a worm wheel mounted on said elevating member and turning therewith in either direction, a supplementary shaft 105 mounted in a plane adjacent the lower end of said elevating member, a worm carried by said shaft and adapted to be engaged by said worm wheel, means for braking and automatically stopping the descent of said elevating member, and means operated by said supplementary shaft for actuating said breaking and stopping means.

3. In a jack, a vertically extending elevating member, means to operate said elevating member, a worm wheel mounted on said elevating member and turning therewith in either direction, a supplementary shaft 110 mounted in a plane adjacent the lower end of said elevating member, a worm carried by said shaft and adapted to be engaged by said worm wheel, means for braking and automatically stopping the descent of said elevating member, means operated by said supplementary shaft for actuating said braking and stopping means.

4. In a jack, an elevating and lowering 130

means, gearing for actuating said lowering and elevating means, a worm wheel connected to said elevating means near the bottom thereof; a supplementary shaft mounted 5 below the shaft by which said operating gearing is driven, a worm on said supplementary shaft meshing with said worm wheel; said worm and worm wheel being capable of turning in either direction with the elevating and lowering means, and means connected with said supplementary shaft tending to lock said jack from descent, and means to control the extent of said locking, whereby the jack may descend freely, be 10 controlled in its descent, or be entirely locked.

5. In a jack, an elevating and lowering means, a main shaft, gearing driven by said shaft for actuating said lowering and elevating means, a worm wheel connected to said elevating means near the bottom thereof, a supplementary shaft located below said main shaft, a worm on said supplementary shaft meshing with said worm wheel, said worm and worm wheel being capable of turning in either direction with the elevating and lowering means, and means connected with said supplementary shaft tending to lock said jack from descent, and means to control the 25 extent of said locking, whereby the jack may descend freely, be controlled in its descent, or be entirely locked, all of said parts being inclosed in a single casing.

6. In a jack, an elevating screw and nut, a stationary casing mounted on the base of the jack, a sleeve actuated by said screw and travelling in said casing; a bearing for supporting said screw, gearing carried by said screw, actuating gearing for engaging the 35 first mentioned gearing, a ratchet and pawl connected with said actuating gearing, a supplementary shaft located transversely to said elevating screw, a worm mounted thereon, said shaft being journaled in the casing, a worm wheel connected to the first mentioned gearing and turning therewith in both directions, and engaging with said worm, a second supplementary shaft journaled in said casing, gearing connected with the first 45 supplementary shaft, a brake drum mounted on the second shaft, a brake ring surrounding said drum adjacent thereto having a plurality of cutaway cam shaped portions, rollers in said cutaway portions, yielding means for forcing said rollers into position to lock said drum and ring when the jack is descending, and a plurality of unlocking fingers for controlling said locking and braking action between the rollers, the drum, and the ring, and means for controlling the movement of 55 said fingers, whereby the descent of the jack may be controlled as desired.

7. In a jack, an elevating screw and nut, a stationary casing mounted on the base of the jack, a sleeve actuated by said screw and

travelling in said casing, a bearing for supporting said screw, gearing carried by said screw, actuating gearing for engaging the first mentioned gearing, a ratchet and pawl connected with said actuating gearing, a 70 transversely located supplementary shaft, a worm mounted thereon, said shaft being journaled in the casing, a worm wheel connected to the first mentioned gearing and turning therewith in both directions, and engaging with said worm, a second supplementary shaft journaled in said casing, gearing connected with the first supplementary shaft, a brake drum adjacent thereto having a plurality of cutaway cam shaped portions, 75 rollers in said cutaway portions, yielding means for forcing said rollers into position to lock said drum and ring when the jack is descending, and a plurality of unlocking fingers for controlling said locking and braking action between the rollers, the drum, and the ring, and means for controlling the movement of said fingers, whereby the descent of the jack may be controlled as desired, said brake drum and said gearing being located at the base of the jack. *

8. In a self-lowering lifting jack, a standard having a chamber at one side of its lower end; a ram reciprocable in said standard; a nut in said ram; a rotatable screw in said 90 nut; a gear on the lower end of said screw; a driving gear meshing therewith; a worm gear beneath said screw gear and rotatable therewith; a worm meshing with and rotatable by said worm gear; and mechanism 95 within said chamber actuated by the rotation of said worm for retarding the movement of said ram during the lowering thereof.

9. In a self-lowering lifting jack, a standard having a chamber at one side of its lower end; a ram reciprocable in said standard; means for imparting reciprocatory movement to said ram including a gear rotatable about the axis of said ram; a driving gear meshing with said rotatable gear; a worm 105 gear beneath said rotatable gear and revoluble therewith; a worm meshing with and rotatable by said worm gear; and mechanism actuated by the rotation of said worm and enclosed within said chamber for retarding 110 the movement of said ram during the lowering thereof.

10. In a self-lowering lifting jack, a standard having a chamber at one side of its lower end; a ram reciprocable in said standard; means for imparting reciprocatory movement to said ram including a gear rotatable about the axis of said ram; a driving gear meshing with said rotatable gear; a bearing plate beneath and revoluble with said rotatable gear provided with worm gear teeth; a worm meshing with and rotatable by said worm gear teeth; anti-friction members supporting said bearing plate; and mechanism 120 within said chamber actuated by the rotation 125 of said chamber.

of said worm for retarding the movement of said ram during the lowering thereof.

11. In a self-lowering lifting jack, a standard provided with a lateral hub and having a chamber at one side of its lower end; a removable bushing in said hub; a ram reciprocable in said standard; means for imparting reciprocatory movement to said ram including a gear rotatable about the axis of said ram; a driving gear meshing with said rotatable gear having its shaft positioned in said bushing; a worm gear beneath said rotatable gear and revoluble therewith; a worm meshing with and rotatable by said worm gear; and mechanism within said chamber actuated by said worm for retarding the movement of said ram during the lowering thereof.
12. In a self-lowering lifting jack, a stand-

ard having a chamber at one side of its lower end; a base threaded to the lower end of said standard; a ram reciprocable in said standard; means for imparting reciprocatory movement to said ram including a gear rotatable about the axis of said ram; a driving gear meshing with said rotatable gear; a worm gear beneath said rotatable gear and revoluble therewith; a worm meshing with and rotatable by said worm gear; a bearing disk positioned on said base; anti-friction members between said disk and worm gear; and mechanism within said chamber actuated by said worm for retarding the movement of said ram during the lowering thereof.

In testimony whereof, I affix my signature.

CHARLES W. RIPSCH.
